DESIGN FOR A HAND STAMP

Ronald K. Duke, Los Angeles, Calif.

Application February 19, 1946, Serial No. 126,691

Term of patent 14 years

(Cl. D64—10)

To all whom it may concern:

Be it known that I, Ronald K. Duke, a citizen of the United States, residing at Los Angeles, county of Los Angeles, and State of California, have invented a new, original, and ornamental Design for a Hand Stamp, of which the following is a specification, reference being had to the accompanying drawing, forming part thereof.

Fig. 1 is a perspective view of a hand stamp embodying my new design.

Fig. 2 is a plan view thereof.

Fig. 3 is a front elevational view of the stamp.

Fig. 4 is a side elevational view thereof.

The essential features of my design reside in the parts shown in full lines.

I claim:

The ornamental design for a hand stamp, substantially as shown and described.

RONALD K. DUKE.
